Application August 20, 1941, Serial No. 407,519

8 Claims. (Cl. 62—115)

This invention relates to compression type refrigerating systems, and it is an object of the invention to provide an improved multiple-stage compression type refrigerating system which is capable of producing relatively low temperatures efficiently and economically.

When it is desired to produce relatively low temperatures by means of a compression type refrigerating system, it is expedient to utilize multiple-stage compression of refrigerant vapor, and to effect cooling of the refrigerant gas between the two or more stages of compression. Such cooling may be effected by evaporation of refrigerant in such a system at a pressure higher than that of the evaporator and lower than that of the condenser.

I provide a system of refrigeration embodying these known concepts, but having new structure and relationship of parts useful to provide heat interchange at a relatively high rate in a small space, and to permit the use of a high temperature evaporator which need not be insulated.

The accompanying drawing shows more or less diagrammatically a refrigerating system embodying my invention.

The numeral 1 designates a low temperature evaporator of any desired construction or type, illustrated as employed to maintain a relatively low temperature within an enclosure 2 having a wall 3. Refrigerant liquid is supplied to evaporator 1 through supply line 4, and is admitted to the evaporator under the control of an expansion valve 5, which may be of any desired type, but which is preferably adapted, in combination with thermal bulb 6, attached to suction line 7 and in heat exchange relation therewith, to control in conventional manner the superheat of refrigerant vapor passing from the evaporator.

Suction line 7 delivers refrigerant vapor to manifold 8, serving the intakes to low-pressure compressor cylinders 9, operating in multiple arrangement. As illustrated, the low pressure cylinders 9, and high pressure compressor cylinder 10, are integral parts of a unitary compressor apparatus driven through shaft 11 by any suitable means, such as an electric motor, but it is to be understood that the invention is not limited to the use of such unitary compressor apparatus, or any particular number or arrangement of compressor stages, but may be embodied in any system utilizing stage compression of refrigerant.

Refrigerant gas delivered from the low pressure cylinders 9 is received within manifold 12 and thence passes through line 13, which projects within and terminates proximate the bottom of a receptacle 15 serving as a high temperature evaporator. When the system is operative in the intended manner, evaporator 15 contains refrigerant liquid, and the refrigerant vapor

passing from the open end 14 of line 13 bubbles up through such liquid.

Vapor is relieved from the top of evaporator 15 through outlet 16 and is routed through a coil 17 disposed exteriorly of high temperature evaporator 15 but within refrigerant liquid receiver 18, so that the gas in such coil is in heat exchange relation with refrigerant liquid contained within receiver 18. This heat exchange desirably cools such refrigerant liquid, and insures against the entry of particles of liquid refrigerant into compressor cylinder 10, by vaporizing any such liquid particles as may be entrained by the gas passing through outlet 16. The refrigerant gas leaving coil 17 passes through line 19 to the intake of high-pressure compressor cylinder 10.

The gas passing through pipe 19 will be substantially cooler than the gas passing to evaporator 15 through line 13. This cooling of the refrigerant vapor discharged from the cylinders 9, prior to its delivery to high-pressure cylinder 10, serves substantially to increase the volumetric efficiency of the compressor.

The refrigerant vapor discharged at relatively high pressure from cylinder 10 is delivered through line 20 to condenser 21, which may be of any desired type or construction, where it is liquefied. The resultant condensate is delivered through line 22 to the upper end of liquid receiver 18, and, after circulating therethrough in heat exchange relation with high-temperature evaporator 15 and coil 17, is relieved from the bottom of receiver 18 through line 23, which discharges into high temperature evaporator 15. Expansion valve 24 controls the admission of refrigerant from the receiver, which is at high pressure, to the evaporator 15, which is at a lower pressure. Expansion valve 24 is under the control of thermal bulb 25, thermally bonded to line 19, preferably, at the point where such line passes out of receiver 18, so that the evaporation of refrigerant within evaporator 15 is controlled to provide the desired degree of superheat in the refrigerant vapor passing to the intake of the high pressure stage of the compressor.

Since the pressure within evaporator 15 is lower than that within receiver 18, some of the refrigerant liquid admitted to the evaporator through line 23 evaporates, forming what is known as "flash gas." The evaporation of such portion of the refrigerant admitted through line 23 serves to cool the remainder, so that the refrigerant liquid within evaporator 15 is at a lower temperature than that within receiver 18 but outside of the evaporator 15.

The "flash gas" formed in evaporator 15 is relieved therefrom through outlet 16, along with the refrigerant vapor supplied within the evaporator 15 by line 13. Refrigerant liquid is re-

lieved from the bottom of high temperature evaporator 15 through supply line 4, which, as set forth above, supplies it to the low temperature evaporator 1, thus completing the refrigerating cycle.

Since evaporator 15 is formed of material having relatively high heat conductivity, there is effected a substantial transfer of heat between the relatively cool liquid within the evaporator 15 and the refrigerant liquid immediately surrounding such evaporator. Such pre-cooling of the refrigerant in receiver 18 will be appreciated as being extremely desirable when it is realized that all cooling of refrigerant liquid which can be effected before the refrigerant is expanded at the point where the useful work of refrigeration is to be accomplished permits greater operating efficiency and greater refrigerative effect at such point. For the same reason, the further cooling of refrigerant liquid within high temperature evaporator 15 by evaporation of a portion thereof serves to promote efficiency of the system.

If desired, test valves 26 and 27 may be provided, the former serving receiver 18 and the latter, through tube 28, serving high temperature evaporator 15.

Various changes and modifications may be made within the scope of the invention as set forth in the following claims.

What is claimed is:

1. Refrigerating apparatus comprising a multiple stage compressor, a condenser, a receiver, a low temperature evaporator, a high temperature evaporator arranged in heat exchange relation with said receiver, a conduit including a pressure reducing valve for conducting liquid from said receiver to said high temperature evaporator, and a second conduit including a second pressure reducing valve for conducting liquid from said high temperature evaporator to said low temperature evaporator.

2. In a refrigerating apparatus comprising a low-temperature evaporator, a condenser, and a multiple stage compressor, the combination of a liquid receiver receiving refrigerant liquid from said condenser, and a high-temperature evaporator disposed within said receiver and receiving refrigerant liquid therefrom and supplying liquid refrigerant to said low-temperature evaporator, said high-temperature evaporator being connected to the outlet of a low pressure stage of said compressor apparatus and receiving gas discharged therefrom, and being connected also to the inlet of a high pressure stage of said compressor apparatus and supplying gas thereto.

3. In a refrigerating apparatus comprising a low-temperature evaporator, a condenser, and a multiple stage compressor, the combination of a liquid receiver receiving refrigerant liquid from said condenser, and a high-temperature evaporator disposed within said receiver and receiving refrigerant liquid therefrom and supplying liquid refrigerant to said low-temperature evaporator, said high-temperature evaporator being connected to the outlet of a low pressure stage of said compressor apparatus and receiving gas discharged therefrom, and being connected also to the inlet of a high pressure stage of said compressor apparatus and supplying gas thereto, and a valve regulating the supply of refrigerant liquid to said high temperature evaporator from said receiver in accordance with variations in the temperature of gas passing to the inlet of

said high pressure stage of said compressor apparatus.

4. In a refrigerating apparatus comprising a low-temperature evaporator, a condenser, and a multiple stage compressor, the combination of a liquid receiver receiving refrigerant liquid from said condenser, and a high-temperature evaporator disposed within said receiver and receiving refrigerant liquid therefrom and supplying liquid refrigerant to said low-temperature evaporator, said high-temperature evaporator being connected to the outlet of a low pressure stage of said compressor apparatus and receiving gas discharged therefrom, and being connected also to the inlet of a high pressure stage of said compressor apparatus and supplying gas thereto, the connection between said high-temperature evaporator and the inlet of said high pressure stage of said compressor apparatus including a conduit disposed without said high-temperature evaporator and within said receiver, whereby refrigerant flowing through said conduit from said evaporator receives heat from refrigerant liquid in said receiver, cooling such liquid, and whereby the passage of refrigerant liquid to said compressor apparatus is avoided.

5. In a refrigerating apparatus comprising a low temperature evaporator, a condenser and a compressor, a liquid receiver adapted to receive condensed refrigerant from said condenser, and a high temperature evaporator wholly contained within said receiver and adapted to receive refrigerant liquid therefrom, said high temperature evaporator being provided with an outlet in an upper portion thereof communicating with said compressor, and with another outlet in a lower portion thereof communicating with said low temperature evaporator.

6. In a refrigerating apparatus comprising a low temperature evaporator, a condenser, and compressor apparatus having a low pressure stage and a high pressure stage, the combination of a liquid receiver connected to said condenser and receiving refrigerant liquid therefrom at condenser pressure, a high temperature evaporator arranged in heat exchange relation with liquid in said receiver, said high-temperature evaporator being connected to the inlet of said high pressure stage of said compressor apparatus for delivery of gas thereto, and a device to control flow of refrigerant from said receiver into said high temperature evaporator at a pressure corresponding substantially to the pressure at the inlet to said high pressure stage, whereby refrigerant passing from said receiver to said high temperature evaporator is subjected to a reduction of pressure in consequence of which a portion of such refrigerant is evaporated, said high temperature evaporator being connected to said low temperature evaporator and supplying relatively cool liquid refrigerant thereto for evaporation therein at reduced pressure corresponding substantially to the pressure at the inlet to said low pressure stage of said compressor apparatus.

7. Refrigerating apparatus as set forth in claim 1 in which said high temperature evaporator is located within said receiver.

8. Refrigerating apparatus as set forth in claim 1 in which said high temperature evaporator is located within said receiver, and said pressure reducing valves are thermostatic expansion valves.

CLYDE E. PLOEGER.
